BY HIS ATTORNEY
Thomas S. Fox

UNITED STATES PATENT OFFICE.

THOMAS S. FOX, OF NEW YORK, N. Y.

PRINTING PROCESS.

1,074,254.

Specification of Letters Patent. Patented Sept. 30, 1913.

Application filed May 21, 1908. Serial No. 434,207.

To all whom it may concern:

Be it known that I, THOMAS S. FOX, a citizen of the United States, residing at 100 Park Place, borough of Brooklyn, city of New York, in the county of Kings and State of New York, have invented certain new and useful Improvements in Printing Processes, of which the following is a specification, reference being had therein to the accompanying drawing.

My invention relates to improvements in a process for the treatment of printing surfaces and has to do with the formation, arrangement and relation of said surfaces.

Any printing surface adapted to receive and deposit ink at points and in quantities predetermined has the advantage of producing great range of finished color values such as in the three color process where the delicate pink of a portrait and the intermediate shades down to the solid red, are printed at one impression, whereas if produced from printing surfaces not adapted to receive and deposit ink at points and in quantities predetermined, separate impressions would be required for the pink and the red which would appear in solid colors, and when two or more impressions, from printing surfaces adapted to receive and deposit ink at points and in quantities predetermined, are made upon the same receiving surface, unless each color value is at a certain angle to other color values, objectionable geometrical effects known as "pattern", result. (See United States Letters Patent to Kurtz 498,396).

In the three color process, uniformly ruled screens are interposed during the preparation of the printing plates for the purpose of photographically producing parallel marks upon each printing plate surface in such a manner that the marks produced by one printing surface in the picture are at an angle of from 20 degrees to 30 degrees to the marks produced by other printing plate surfaces in the same picture. The commercial possibility of representing finished even tints of shades of different colors in a picture by three impressions is due to the measured arrangement of the marks to each other upon each printing surface and the measured relation of the marks upon one printing surface to the marks upon other printing surfaces used in the production of the same picture. Dark effects are pro-

duced by printing yellow, red and blue over each other, and subjects having dark, sharp edged effects such as the rigging of ships, flag poles and bare tree branches are usually printed by successively applying 60 these three colors and therefore require exact register to prevent "rainbow effects." This three color half-tone process is unsuited for newspaper work because the paper stretches and destroys the register, and because colors printed over each other in rapid succession while moist, do not deposit well, resulting in brown smudge instead of black. 65

In my process I employ a black feature or what is known as a key printing surface, 70 plate or stone for the black parts, details, and general "modeling." This key printing surface may comprise any kind of marks such as grain, dots, lines or stippling, but preferably comprises a half-tone plate produced by a uniformly ruled screen, and one which has been over-exposed or etched so that the dots printed thereby are very small in the higher lights. In carrying out 75 my process, this half-tone plate may be produced in the usual way from a subject, and a proof may be taken and colored by hand to serve as a guide or proof to show where and how much color is desirable in the printed subject. I also prepare in the ordinary way upon other suitable surfaces, such as zinc, transferred duplicates of the key 80 printing surface, and upon these I mechanically "model," fill in, treat, or mark preferably by placing the various marks such as 85 dots, as the disposition of the color values on the color proof indicates. By "modeling", filling in, treating, or marking, I mean as an artist would model a picture except that instead of using a brush, pencil 90 or similar tool, the graduation of color or shades comprises marks of different sizes, forms or relative position, as above stated. For this operation, I prefer to support a 95 marking member or medium having arranged physical features, preferably such as a flexible, transparent film. (See United States Letters Patent to Day, 214,493 and 250,211) and the surface of each zinc or other member to be treated or marked and 100 used as a printing surface, in parallel planes and in such a manner that the angular relation of said marking member and said member to be marked may be measurably 105 changed and a relative lateral movement im- 110

parted while they are in said parallel planes; that is to say, I may measurably rotate or measurably move in a straight line, either or both the marking member or the member to be marked, while said members are in parallel planes, and for this purpose it has been found convenient to use the apparatus set forth in my application for Letters Patent of the United States now pending and bearing the Serial Number 232,999. This enables me to definitely predetermine an angle at which the rows of marks upon one surface will run to the rows of marks placed upon other surfaces which are to be used as printing members in the same picture, and I am also able to elongate any of said marks into lines running in the same direction as said rows of marks.

Subjects such as I have mostly to do with have lights and shades, and as the marks that represent the light must be small, I may employ films whose design faces will mark small dots, and in proportion as the shades or tones increase in color value, I may shift either of the members so that the dots may be elongated until they connect with other dots forming lines, and to obtain still greater color values, said formed lines may be extended transversely or thickened, until they meet other lines, thereby forming solid masses. To insure exact harmony, the marks or features of my films are preferably in parallel rows of right angle formation, equally spaced and of equal size.

In the production of a color job, say in four colors, such as red, yellow, blue and black, I prefer to do all of my marking for the same job with a single film, or several films having marks of the same formation, arrangement and number to the inch. This rule may be varied, as for instance the surface of the zinc intended to print the yellow, or any other color, or two of such surfaces, may be marked or treated with a film having a different design face to the design face of the film used for the other printing surfaces to be used in the same job. I also prefer that my half-tone key surface comprise the same number of marks to the inch as the number of marks to the inch upon the marked or treated surfaces, but the number of marks to the inch upon the surface of any printing member may be a multiple of the number of marks to the inch upon the surface of any other printing member used in the same job.

I do not confine my process to the uniform arrangement of marks upon the surfaces of all the printing members to be used in the same picture, as it may be desirable to vary the composition of color value in some parts of a picture by arranging the marks upon some of the printing surfaces irregularly, as in stipple, and where the uniform composition of the several surfaces to be used in the

same picture, varies, so may the manner in which some are produced. In fact, it may not be desirable at all times to have a strictly regular composition of color value throughout a picture and I do not limit myself to such composition, but I may use such composition of colors alone or in combination with irregularly combined color. I may also use a key plate composed of irregular lines as in a pen drawing, or a plate having dots, grains, stippling or marks of irregular formation; in such cases the color plates are preferably modeled with films having marking surfaces composed of regularly spaced dots at angles varying from 23 to 30 degrees.

Referring to the accompanying drawings, Figure 1 represents a print of a boat scene produced from a key plate marked at 45 degrees and adapted to print the black as indicated by the reference character 5. Fig. 2 is a print from a plate marked at 75 degrees and adapted to print the yellow as indicated by the reference character 6. Fig. 3 a print from a plate marked at 105 degrees and adapted to print the red as indicated by the reference character 7. Fig. 4 a print from a plate marked at 15 degrees and adapted to print the blue as indicated by the reference character 8; all of said plates for the same colored job.

In order to determine the arrangement and amount of color which should be deposited by the plates used in the prints shown in Figs. 2, 3 and 4, a print from the half-tone key plate used in Fig. 1 is first colored by hand and used as a guide while "modeling" the other plates for the same job, after which each plate is successively applied with its respective ink in the production of the finished picture.

Various modifications may be made without departing from the spirit of the invention.

Having described my invention, what I claim as new and desire to secure by Letters Patent, is:

1. The process of making multi-colored surfaces consisting in preparing a key printing surface and three other printing surfaces having transfers of said key printing surface, producing marks on said key printing surface at an angle of about 45 degrees and producing the marks on said other three printing surfaces at angles of about 15, 75 and 105 degrees respectively, and printing from all of said printing surfaces.

2. The process of making multi-colored surfaces consisting in preparing a key printing surface and three other printing surfaces having transfers of said key printing surface, producing one kind of marks at an angle of about 45 degrees on said key printing surface and producing another kind of marks arranged at angles of about 15, 75

and 105 degrees respectively on said other three printing surfaces, and printing from all of said printing surfaces.

3. The process of making multi-colored surfaces consisting in preparing a key printing surface and three other printing surfaces having transfers of said key printing surface, producing one kind of marks at an angle of about 45 degrees on said key printing surface and producing three other kinds of marks arranged at angles of about 15, 75 and 105 degrees respectively on said other three printing surfaces, and printing from all of said printing surfaces.
- 10 4. The process of making a multi-colored picture consisting in preparing a printing

surface and three printing surfaces having transfers therefrom, producing marks upon each of said surfaces by the use of a printing film, said marks upon any one of said 20 surfaces at an angle of from about 23 to about 30 degrees to the marks upon another of said surfaces, and printing from all of said printing surfaces upon said multi-colored picture.

25 In testimony whereof I affix my signature in presence of two witnesses.

THOMAS S. FOX.
